UNITED STATES PATENT OFFICE

MARK MORAN, OF SEATTLE, WASHINGTON

CONTINUOUS-FEED WRITING TABLET

Application filed December 19, 1925. Serial No. 76,426.

My invention relates to improvements in continuous feed writing tablets and is in the nature of an improvement on the continuous feed writing tablet disclosed in my prior Patent No. 1,491,055, issued April 22, 1924.

The object of my invention is to improve and simplify the construction of continuous feed writing tablets of the class in which the paper is drawn forwardly under the platen and then up over the platen and to cheapen the cost of manufacture of the same and render said writing tablets more substantial and durable and more reliable and efficient in operation.

More specific objects are:

To provide a continuous feed writing tablet in which the entire frame including the platen over which the paper passes is made from a single piece of sheet metal;

To provide simple and efficient paper feed means that may be conveniently operated by one hand to advance the paper without danger of moving or sliding the tablet around on the desk or table on which it rests thus leaving the other hand free for other uses;

To provide novel means, in connection with said paper feed, for supporting the feed rollers and providing room for the same;

To provide, at the location where the paper is discharged and torn off, an upwardly inclined discharge passageway that directs the end of the paper upwardly so that said end may be easily grasped by the fingers to tear it off;

To provide inturned edges forming paper supports along the bottom sides of the frame;

To provide efficient means for receiving and holding a spindle or shaft on which a roll of paper is mounted in such a manner that said spindle is easily inserted and removed but is not liable to be accidentally displaced.

To provide a frame having an inclined head end that may be secured to a wall so as to support the platen at a convenient angle for use; and to provide a removable weight for use within writing tablet frames of smaller sizes to give said smaller frames stability when they are to be used on desks or tables

said weight being omitted from frames that are to be secured to walls.

Other and more specific objects will be apparent from the following description taken in connection with the accompanying drawings.

In the drawings Figure 1 is a view in perspective of a continuous feed writing tablet constructed in accordance with my invention as it may appear without any paper therein.

Fig. 2 is a view in longitudinal section of the same with a roll of paper in it.

Figs. 3 and 4 are cross sectional views on broken lines 3-3 and 4-4 respectively of Fig. 2.

Fig. 5 is a fragmentary perspective view of the portion of the frame in which the feed rollers are mounted, the cover plate or cap for the feed rollers being removed.

Fig. 6 is a view in side elevation showing a modified form of frame having an inclined rear end adapted to be secured to a wall.

Figs. 7 and 8 are sectional views substantially on broken lines 7-7 and 8-8 of Fig. 6.

Like reference numerals designate like parts throughout the several views.

In the drawings I show a frame, preferably formed of a single piece of sheet metal, and embodying two side members 10 and 11 whose top edges are connected toward one end by an integral platen 12 that extends on a slight upward incline from the foot end of the frame to a point about half way to the head end of the same. The foot end of the platen is bent to form a roll 13 around which the paper may pass as shown in Fig. 2. A guide bar 14 under which the paper must pass extends across the foot end of the platen 12 directly above the roll 13 to hold the paper down onto the platen. For the purpose of this description I have called the end of the frame that supports the paper roll the head and the other end the foot.

Near its upper or head end the platen 12 is cut away to form a transverse opening 15 within which the peripheral portions of two rollers 16 and 17 may operate. Parts of the metal that is stamped out in forming the opening 15 is bent up at each side to form lugs 18 that serve as end walls for an upper

roller housing and bearing or guide plates for a shaft 20 on which the upper roller 16 is mounted. Slots 21 in the end walls 18 permit the shaft 20 of upper roller 16 to move vertically. The lower roller 17 has a shaft 22 that is journaled in the sides 10 and 11 of the frame and that is provided on one end with a hand wheel 23 that may be conveniently grasped by the fingers preferably of the right hand to turn the lower roller and feed the paper. The roller shafts 20 and 22 are both provided near both ends with annular grooves 24 wherein tension springs 25 may engage, the tension springs serving as means for yieldingly urging the two rollers together and further serving as a part of the bearing means for the shaft 20 of the upper roller 16.

A transverse strip of metal 26 is left on the discharge side of the slot 15 said strip being a continuation of the platen 12 except that it is inclined upwardly at a sharper angle to cause the discharging end of the paper 27 from a roll 28 to be directed upwardly so that said discharge end will be clear of the roll and may be more readily grasped to pull out and tear off.

A curved cap 30 is secured to and supported by inwardly bent portions 31 on the lugs 18 in such a manner as to form a housing for the upper roller 13 and completely cover the slot 15. The rear edge of cap 30 is bent outwardly and upwardly to form a tear off strip 32 and to cooperate with the strip 26 in forming a guide for the discharging paper. It will be noted that the lower roller 17, when rotated pulls the paper that is drawn thereunder in the proper direction. Also that the paper reverses sides in passing around the platen, the side that is uppermost on the roll being next to the platen. This makes it possible to display advertisements on the roll and have the reverse side of the paper uppermost on the platen.

The lower edges of the sides 10 and 11 are bent inwardly to form flanges 33 that greatly strengthen the frame and that serve to support the paper between the feed roll 17 and the foot end of the frame.

The sides 10 and 11 of the frame extend upwardly toward the head end of said frame to form rounded portions 34 which are provided with vertical grooves 35 terminating in deeper recesses 36 for the reception of the ends of a spindle or bar 37, preferably square, on which the roll 28 of paper is supported. The upper ends of the grooves 35 are flared outwardly as at 38 to facilitate insertion of the ends of the bar 37 therein when a roll of paper is on said bar and the recesses 36 are deep enough to afford sufficient shoulders 40 above the ends of the bar 37 to prevent said bar and roll of paper from dropping out of the frame if said frame is inverted. In inserting or removing the bar 37 the side por-

tions 34 are sprung outwardly enough to permit the ends of the bar to pass. The bar 37 being square prevents the paper from unrolling too freely. The side members 10 and 11 of the frame are connected at the rear by a head end piece 41, preferably of angular shape, that affords the necessary strength for that end of the frame structure.

The paper 27 from the roll 28 passes off of said roll, under the roller 17 thence forwardly on the flanges 33, thence upwardly around the end roll 13 and under the guide or breaker strip 14 thence over the platen 12, between the rollers 16 and 17 and out between the discharge plates 26 and 32. The paper resting on the platen 12 may be conveniently written on, beginning near the top end or housing 30 and writing downwardly toward the foot of the platen. Only the part that is written on need be torn off thus making possible a considerable saving in paper over a tablet of this class in which the paper is fed from the roll downwardly over the platen and torn off at the bottom: for instance if a single line as a telephone number is written at the top of sheet on the platen the paper may be pulled out just far enough to clear the writing and a comparatively narrow strip of paper torn off. On the other hand a long message or series of messages may be written continuously, the paper being fed through as used and the length of one continuous writing being limited only by the length of the paper on the roll.

The guide strip 14 bends and holds the paper down at the foot or bottom end of the platen so that it may be conveniently written on adjacent said guide strip. The roller 17 may be turned with one hand and without moving the tablet on the desk or table on which it rests thus providing a force feed which obviates the necessity of pulling the paper out.

In Figs. 6, 7, and 8 I show a continuous feed writing tablet of smaller size in which all of the essential elements are substantially the same as those shown in the preceding figures, but in which the platen is disposed at a greater angle relative to the base to afford space within the frame for a weight 45 removably held therein as by screw 46, and in which the rear end 47 is inclined as shown to adapt it to fit squarely against and be secured, as by screws 49, to a wall 48 so as to support the frame at the most convenient angle to be written on. A rest 50 for the hand or arm may be secured to the frame, when the tablet is to be used on the wall. The weight 45 is used to give additional stability to the frame of the small size tablet when the same is used on a table or desk and said weight will be removed from or left out of tablets that are intended for use on walls. The arm rest 50 obviously will not be used on tablets that are used on desks or tables.

Said rest 50 is preferably foldable, see dotted lines.

The foregoing description and accompanying drawings clearly disclose a preferred embodiment of my invention but it will be understood that this disclosure is merely illustrative and that such changes in the invention may be resorted to as are within the scope and spirit of the following claim.

5 10 I claim:

In a continuous feed writing tablet, a frame embodying two spaced apart side members, a platen supported on said side members and having an upward incline from the foot toward the head of the frame, said platen having a transverse slot formed near the head end and leaving a transverse discharge member beyond said slot that is inclined upwardly at a greater angle than said platen, bearing lugs extending upwardly from said side members at the ends of said slot, said bearing members having slotted holes therein, an upper roller having spindles that extend outwardly through said slotted holes, a lower roller below said upper roller and arranged to press against said upper roller, tension springs connecting the bearing spindles of said two rollers, thumb turn means for turning said lower roller a cap supported by said lugs and forming a housing for said upper roller and an extension on the rear end of said cap spaced above said discharge member and forming a tear off strip.

The foregoing specification signed at Seattle, Washington, this 5th day of December, 1925.

MARK MORAN.
